US0D1063571S

(12) United States Design Patent (10) Patent No.: US D1,063,571 S
(45) Date of Patent: * Feb. 25, 2025

(54) FOOD HOLDER

(71) Applicant: Belgo Holdings LLC, Brooklyn, NY (US)

(72) Inventor: Thomas DeGeest, Denver, CO (US)

(73) Assignee: Belgo Holdings LLC, Brooklyn, NY (US)

() Term: 15 Years

(21) Appl. No.: 29/823,894

(22) Filed: Jan. 20, 2022

(51) LOC (15) Cl. 09-03

(52) U.S. Cl.

USPC D7/701

(58) Field of Classification Search

(57) CLAIM

The ornamental design for an food holder as shown.

DESCRIPTION

FIG. 1 is a perspective view of a food holder showing my new design in an open state;

FIG. 2 is a top plan view thereof;

FIG. 3 is a bottom plan view thereof;

FIG. 4 is a left side view thereof;

FIG. 5 is a right side view thereof;

FIG. 6 is a front view thereof; and,

FIG. 7 is a rear view thereof.

The broken dash-dot lines shown in FIGS. 1-7 are for illustrative purposes only and form no part of the claimed design. The dot-dash lines shown in FIGS. 1-7 are included to represent fold lines and form no part of the claimed design.

1 Claim, 7 Drawing Sheets
